[57] ABSTRACT

A sheet metal coupling pin for driving a rotatable cutter of a dry-shaver, which cutter is capable of limited tilting movement and is formed with a coupling slot, the coupling pin being formed with rounded portions the radii of curvature of which are in a given relationship with the length and the width of the slot.

COUPLING PIN FOR AN ELECTRIC DRY-SHAVER

BACKGROUND OF THE INVENTION

The invention relates to a metal coupling pin for use in an electric dry-shaver having at least one shaving head capable of limited tilting movement, where a cutter comprises a plurality of blades, and is adapted to be rotatably driven and co-operates with the shaving head. A coupling member which is also adapted to be rotatably driven, is capable of limited tilting movement, at its end nearer the cutter carries the coupling pin and thrusts the coupling pin into engagement with the cutter and hence the cutter into engagement with the shaving head under spring action. The cutter is formed with a coupling slot of rectangular cross-section having parallel walls into which the coupling pin engages so as to cooperate with the shorter walls of the coupling slot by means of portions having a curvature, the radius of which is substantially equal to one half of the width of the longer walls, and to co-operate with the longer walls by means of portions having a curvature the radius of which is substantially equal to one half of the width of the shorter walls.

My co-pending Netherlands Pat. No. 6,810,708 and U.S. Pat. No. 3,748,731 laid open to public inspection describes such a coupling pin. An important requirement is that during operation of the dry-shaver the cutter should always be in engagement with the associated shaving head, because otherwise a rocking movement of the cutter relative to the head is produced. This results in some of the hairs which project through the shear plate not being cut. This rocking movement, which is felt by the user as a disagreeable vibration of the shaving head, is also responsible for uneven wear of the shaving head, so that the incomplete engagement of the cutter with the shaving head is further aggravated.

The coupling pin described in said prior art U.S. Pat. No. 3,748,731 provides satisfactory results, because there is a universal driving relationship between the cutter and the coupling pin. The coupling pin is a hardened steel component, the cylindrical lateral surfaces of which having the said radii of curvature was formed by grinding. Such coupling pins are comparatively expensive, in particular because of the required grinding operation which has to be performed with a comparatively high degree of accuracy on a component which owing to its small size is difficult to handle.

SUMMARY OF THE INVENTION

It is an object of the present invention to provide a coupling pin of the kind described at the beginning of this specification; the manufacture of such coupling pin based on the recognition that dry-shavers of the type in which the coupling pin is to be used always have cutters which are driven in one direction only, can be appreciably simpler, resulting in lower cost. This invention is characterized in that the coupling pin is made of steel sheet, and its portions which cooperate with the longer walls of the coupling slot comprise extensions of the required radius of curvature made by pressing. The coupling pin according to the invention can be manufactured by stamping, which means a considerable simplification of the manufacture.

BRIEF DESCRIPTION OF THE DRAWINGS

In order that the invention may be readily carried

into effect, reference will now be made by way of example to the accompanying drawings, in which

FIG. 1 is a partial sectional view of an electric dry-shaver,

FIG. 2 is an elevation sectional view of the coupling pin of FIG. 1 shown 20 times actual size, which is mounted in the end of a coupling member and cooperates with a cutter part shown in section,

FIG. 3 is a side elevation of the coupling member shown in FIG. 2,

FIG. 4 is a plan view of a coupling member arranged in a rectangular coupling slot of a cutter in a position in which it is slightly rotated about its axis from a substantially parallel relationship with the slot, so that its extensions engage the longer walls of the slot, and

FIG. 5 is an elevation sectional view of the coupling pin and of part of a cooperating cutter taken at right angles to the longer walls of the coupling slot.

DETAILED DESCRIPTION OF THE PREFERRED EMBODIMENT

Referring now to FIG. 1, there is shown a circular shaving head shear plate 1. The head has a number of slits 2 and is capable of limited tilting movement relative to a frame plate 3 which is connected to the housing, not shown, of the dry-shaver. A cutter 4 which is adapted to be rotatably driven and comprises six blades 5 cooperates with the shear plate 1. A coupling member 6, is rotatably driven, is capable of a limited tilting movement, and carries a coupling pin 7 at its end near the cutter. The coupling member 6 has terminal part 7a as the drive end of its coupling pin 7 thrust into engagement with a stop member 30 of the cutter 4 by a compression spring 8 mounted in a recess 9. As a result the cutter 4 is thrust into engagement with the shear plate 1. The cutter 4 is formed with a coupling slot 10 of rectangular section, see in particular FIG. 4, having two pairs of parallel walls 11, 12 and 13, 14. The coupling pin 7 engages in the slot 10 and cooperates with the shorter walls 11 and 12 by means of portions 15 and 16 having a curvature the radius of which is substantially equal to one half of the width of the longer walls 13 and 14, and cooperates with the said longer walls by means of portions 17 and 18 having a curvature the radius of which is substantially equal to one half of the width of the shorter walls 11 and 12. These ears are also bent out of the plane of the sheet material as indicated at 28, 29 in FIG. 4, wherein the radius of the outer surface of the curvature of each of said ears 28, 29 is substantially equal to one-half the length of the short side 11 of the rectangular aperture. With these dimensional parameters it is now feasible to manufacture this coupling pin from flat sheet metal which is cut to shape and then pressed into final shape. This is substantially cheaper than the final shape formed out of a solid block or having same cast. The lower end of the coupling member 6 is widened to form a flange 19 of square cross-section which fits in a chamber 20 of corresponding cross-section formed in a gear-wheel 21. The chamber 20 is closed by means of a spring clip 22. On its other surface the gear-wheel 21 has a hub 23 in which a bore 24 is formed in which fits a pin 25, the other end 26 of which is knurled and pressed into a mounting plate 27. The gear-wheel 21 can be driven by a rotating electric motor via a transmission gear, not shown, the coupling member 6 transmitting the rotary movement to the cutter 4.

I claim:

1. In a shaving head of a rotary dry shaver including a shear plate tiltably mounted within a housing, a rotatably cutter positioned for engaging said shear plate, drive means for imparting rotary motion, a coupling member having a first part engaged and driven by said drive means and a drive end formed as a coupling pin for engaging and driving said cutter, and spring means engaging and urging said coupling pin axially against said cutter which is correspondingly urged axially against said shear plate, the improvement in combination therewith wherein said cutter has defined therein a central, rectangular aperture defining a pair of long side-walls and a pair of side-walls for receiving said coupling pin, and said coupling pin is formed of sheet material and comprises a shank having length and width in the plane of the sheet and thickness, and a drive end which is insertable axially within said aperture and has a pair of ears which extend in the opposite directions widthwise, each bar having a rounded outer edge of radius substantially equal to one-half of the length of one of said long walls, each ear also curved

out of the plane of said sheet about a lengthwise axis, with the outer surface of each ear having a radius about said axis substantially equal to one-half the length of one of said shorter walls.

5 2. Apparatus according to claim 1 wherein said cutter further comprises a stop member covering said aperture and situated intermediate the shear plate and coupling pin and wherein said drive end of the coupling pin has a rounded terminal part which is urged axially into engagement with said stop member.

3. Apparatus according to claim 1 wherein said coupling pin is tiltably mounted relative to said housing.

4. Apparatus according to claim 1 wherein said coupling member is cylindrical with a central bore, and said coupling pin is a separate element mounted for axial movement in said bore and said spring means is situated in said bore and urges said pin axially outward of the bore.

15 20 5. Apparatus according to claim 1 wherein said coupling pin comprises sheet metal.
